DISPENSING CLOSURE

Juel D. Clevenger, Raytown, Mo., assignor to Cook Chemical Company, Kansas City, Mo., a corporation of Missouri

Filed Nov. 19, 1964, Ser. No. 82,687

Term of patent 14 years

(Cl. D58—26)

Fig. 2.

Fig. 3.

Fig. 4.

FIG. 1 is a side elevational view of a dispensing closure, showing my new design;

FIG. 2 is a front elevational view thereof;

FIG. 3 is a rear elevational view thereof; and

FIG. 4 is a top plan view thereof.

The portions shown in broken lines are for illustrative purposes only.

I claim:

The ornamental design for a dispensing closure, as shown and described.
